UNITED STATES PATENT OFFICE.

JAMES MAGEE, OF WESTERLY, RHODE ISLAND, ASSIGNOR OF TWO-THIRDS
TO ALVA A. CRANDALL AND WILLIAM KEENAN, BOTH OF SAME PLACE.

LOOM-SHUTTLE.

SPECIFICATION forming part of Letters Patent No. 308,318, dated November 18, 1884.

Application filed December 6, 1883. (No model.)

To all whom it may concern:

Be it known that I, JAMES MAGEE, a citizen of the United States, residing at Westerly, in the county of Washington and State of Rhode Island, have invented a new and useful Improvement in Loom-Shuttles, of which the following is a full, clear, and exact description, reference being had to the accompanying drawings, forming a part of this specification.

10 The object of my invention is to regulate the tension of the thread as it passes off of the bobbin; and to this end my invention consists in the peculiar and novel construction and arrangement of parts, as hereinafter described and claimed.

15 In order that my invention may be fully understood, I will proceed to describe it with reference to the accompanying drawings, in which—

20 Figure 1 is a plan view of the shuttle with its bobbin and tension-regulating roller in operative position. Fig. 2 is a view, partly in side elevation and partly in vertical section, of one end of the shuttle, showing the tension-regulating device in operative position.

25 In the said drawings, A designates the shuttle-body, and a its eye.

30 B designates the bobbin, and l designates a strand of thread passing off from the bobbin and out through the eye a of the shuttle-body.

35 As my present invention does not relate particularly to the mounting of the bobbin in the shuttle-body, it will suffice to say that the bobbin is mounted on a spindle which passes longitudinally into the body of the bobbin and is hinged at one extremity in the end of the shuttle-body. The hinge is provided with a spring, which serves not only to hold the spindle in operative position, but also to

40 hold the bobbin from moving on the spindle. When the bobbin is depleted, the spindle is raised at its free end and the bobbin is re-

moved. A full bobbin having been placed on the spindle, the latter is depressed and is held down by its hinge spring, and the outer end 45 of said spring also presses from beneath into the notch b of the bobbin, holding the latter from turning or sliding on the spindle. I do not confine myself exclusively to this arrangement of the bobbin, but prefer it to others 50 which may be used.

C designates a cylindrical roller, which extends transversely of the shuttle, and the ends of which are confined between two inverted-U-shaped straps, c, which are secured to the 55 sides of the shuttle-body. This roller C rests upon an inclined plate or shelf, D, the pitch of which is downward toward the free end X of the bobbin. The thread, passing from the bobbin out through the eye, is carried between 60 the roller C and the platform D. The forward edge of the plate D is held by screws, as shown, which pass down into the portion b' of the shuttle-body. The lower ends of the straps c 65 pass through the edges of the plate D, and are bent at right angles beneath said plate. Thus it will be seen that as the thread is fed off of the bobbin it will be kept under a constant tension by the roller C, and all slack and knotting will be avoided.

70 Having thus described my invention, I claim as new and desire to secure by Letters Patent— The combination, with the shuttle-body having the portion b', of the shelf D, secured to said body and inclined toward the free end of 75 the bobbin, the straps c, secured in the sides of the body and bent beneath the shelf D, and the cylindrical roller resting upon the shelf and confined in its movements by the straps, all substantially as described.

JAMES MAGEE.
